Inventor:
Geo. D. Hadley.

United States Patent Office.

GEORGE D. HADLEY, OF CINCINNATI, OHIO, ASSIGNOR TO HIMSELF AND
GARDNER WATERS, OF SAME PLACE.

Letters Patent No. 81,893, dated September 8, 1868.

IMPROVEMENT IN GLOBE-VALVES.

The Schedule referred to in these Letters Patent and making part of the same.

TO ALL WHOM IT MAY CONCERN:

Be it known that I, GEORGE D. HADLEY, of Cincinnati, county of Hamilton, State of Ohio, have invented a new and improved Steam Globe-Valve; and I do hereby declare that the following is a full, clear, and correct description thereof, reference being had to the accompanying drawings, and to the letters of reference thereon marked, making a part of this specification.

This invention relates to a new and improved method of constructing globe-valves for steam purposes, and consists in forming that part of the valve at which its two main portions are united, in a peculiar way, which makes it, it is believed, simpler, better, and cheaper than any other valve of its class.

Instead of the lock-nut ordinarily used for coupling together the two parts of the valve, I form the inner surface of the upper portion of the shell or main body of the valve at its lower end with a thread, and its upper end left blank, and the outer surface of the lower part of what I call the "stand" (marked D in drawing) in a corresponding way, that is, threaded at its lower end and left blank above.

Constructed in this way, the most ordinary hand can easily and readily grind the valve in and to its seat, without disconnection from the pipes to which it may be attached, and without endangering any threads.

The whole exterior surface of the "stand" may be threaded.

The drawing represents the cock in vertical central section, clearly indicating all the parts, and plainly showing the improvement.

C represents the shell or body of the cock; E, the valve; F, the handle, affixed to the stem of the valve; G, the stuffing-box; D, the stand; A *a*, the blank and threaded interior surface of the upper portion of the shell or body of the cock; B *b*, the exterior corresponding blank and threaded surface of the stand.

Now, when the screw *b* is relieved from the screw *a*, and the valve E is bearing upon its seat, it can be readily perceived that the blank portions A and B will form a perfect guide for the purpose of grinding the valve to its seat, without the necessity of removing the handle F or the packing from the stuffing-box G, or the body of the cock itself from the pipes to which it is attached.

I claim a globe-valve, when constructed with a blank surface, A, above the screw *a* in the body or shell of the valve, and the corresponding blank surface, B, above the screw *b* on the stand D, so that when the screw *b* is relieved from the screw *a*, and the valve E is bearing upon its seat, the blank surfaces A and B shall form a perfect guide for the purpose of grinding the valve to its seat, without being obliged to remove the handle or the packing from its stuffing-box, or the body of the valve from its connections.

GEO. D. HADLEY.
